UNITED STATES PATENT OFFICE.

CHARLES HENRY KENNY, OF WINNIPEG, AND MALCOLM McMILLAN, OF GLADSTONE,
MANITOBA, CANADA.

GRAIN-CAR DOOR.

1,018,623.

Specification of Letters Patent.

Patented Feb. 27, 1912.

Application filed August 5, 1909. Serial No. 511,301.

To all whom it may concern:

Be it known that we, CHARLES HENRY KENNY, of the city of Winnipeg, in the Province of Manitoba, Canada, and MALCOLM McMILLAN, of the town of Gladstone, in the Province of Manitoba, Canada, have invented certain new and useful Improvements in Grain-Car Doors, of which the following is the specification.

10 Our invention relates to grain car doors and the object of the invention is to provide a strong and durable metallic door which can be quickly released from a car when desired and which can be quickly placed and stored in the open position within the car.

Further objects of our invention will be hereinafter more fully described and particularly pointed out in the claims.

It consists essentially in a door formed 20 from two metallic sections a corrugated lower section and a reinforced upper section, releasable means carried by one of the door posts adapted to engage with the ends of the sections and to be withdrawn within 25 the door post, means allowing for the folding of the upper section, and means for raising and automatically locking the lower section in the raised position, the parts being arranged and constructed as hereinafter 30 more particularly described.

Figure 1 is a front elevation of a car supplied with our door, the door being shown in the closed position. Fig. 2 is an interior view of the car as in Fig. 1. Fig. 3 is a detailed side elevation of a portion of the lower section of the door showing the links as they appear when the section is locked with the door raised.

In the drawings like characters of reference indicate corresponding parts in each figure.

1 and 2 are the ordinary door posts of a car of which 3 is the upper cross beam and 4 the door sill such parts bounding the usual 45 doorway opening 5.

6 is the roof of the car and 7 are the face boards at the side of the door posts.

8 is the inner wall of the car. The grain door is formed with a lower section 9 and an upper section 10, which when in the closed position overlap the one on the other so as to prevent leakage of grain between them. The lower section is formed from corrugated metal with the corrugations running longitudinally of the section and is of

a height which it is usual to employ with the heavier grains such as wheat.

11 are Z-shaped bars firmly secured to the ends of the lower section by bolts 12. It will of course be understood that the bars 60 will have to be fastened to the section in such a manner that there will be no possibility of grain escaping at the joint formed between the portions. The Z-bars are employed to give flat ends to the section. This 65 might be done by rolling the ends of the section after corrugating but we consider such a more expensive manner of constructing the door.

The door post 2 is provided with an angular vertically extending groove or channel which receives the arm of the Z-bar appearing at the adjoining end of the section 9 when it is in its closed position.

The door post 1 has a vertically extending 75 angle bar 18 secured to its inner face forming a recess which admits a vertically extending channel iron plate 20 slidably between its inner face and the face of the post. The plate is adapted to receive the 80 extending arm of the Z-bar at the adjoining end of the lower section and it is secured within the recess by means of straps 21 fastened at their ends to the plate and looped around bolts 22 passing from the bar into 85 the post. The straps are curved so as to give a different pitch to the various slots with the result that the plate 20 is withdrawn within the recess more quickly at the top than at the bottom when raised upwardly, as will shortly be more apparent. 90 The upper end of the plate is provided with an extending portion 20' which is pivotally secured by a pin 24 to a link 25 pivoted to the post by a pin 26.

95 27 is a U-shaped rod passing through the cross beam 3 above the upper end of the plate 20, the ends of the rod appearing the one 27' at the interior and the other 27" at the exterior of the car. The end 27' of the 100 rod is united with the pin 24 by means of a link 28 and the end 27" is connected through a rod 29 with a hand lever 30 fastened to the face boards 7 by means of a bolt 31.

105 32 is a track secured to the beam 3 and passing from the interior of the car to the exterior.

110 33 are opposing brackets firmly secured to the lower section of the door and having

bars 34 pivotally secured thereto by pins 35. The bars are secured through chains 36 with downwardly extending bars 37 carried by the track 32, the bars being designed to pass 5 freely longitudinally along the track 32. The chains 36 are united by a further chain 38.

39 is a bolt passing through the lower section and having a lever 40 secured to its 10 inner end and a cross bar 41 to its outer end. The cross bar 41 is connected with the lower ends of the bars 34 by means of links 42 which have the ends adjoining the cross bar bent at 43. The upper section 10 of the door 15 is formed from two portions 10' and 10² secured the one to the other by hinges 44. The section is reinforced by angle irons 45 and the upper portion 10' has its lower edge overlapping the upper edge of the lower 20 portion at 46 so as to form a tight joint to prevent the leakage of grain. The ends of the upper section are designed to be received by the channel in post 2 and the plate 20 in the same manner as are the ends of the 25 lower section. When it is desired to store the upper section of the door the lower portion 10² is folded backwardly on the upper section 10' and is held in this position by a pin 47 carried by the upper angle iron of 30 those 45. The pin has a lug 47' thereon which prevents it escaping from the angle iron.

48 are chains suspending the upper section from the track.

35 In order to understand the features of the door we will now describe its operation assuming it closed and the car filled with grain. The lever 30 is thrown upwardly which movement causes the arms 27² and 27' 40 of the rod 27 to pass upwardly. The arm 27' carries with it the link 28 which raises the channel plate 20 the upper end of the plate swinging on the center formed by the pin 26. This causes the channel iron plate 45 to withdraw within the recess and finally disappear so as to free the adjoining edge of the sections. The upper section is freed before the lower section and can be removed first if desired. As soon as the ends of the 50 sections have been released they swing outwardly under the pressure of the grain and free it from the car. Before finally cleaning out the grain remaining within the car the upper section is folded as already described 55 and passes to the interior of the car. The

lever 30 is rotated in the direction indicated by the arrow so as to bring the links 42 to the position shown in Fig. 3 where it will be seen they lock automatically together. The upper ends of the bars 34 swing away from 60 each other and their action on the chains cause the section to be raised clear of the floor of the car and remain in the raised position until released by the lever. When this is done the section is also stored within 65 the car against the wall 8.

What we claim as our invention is:

1. In a device of the class described the combination with the lower section of the door and suitable overhead supporting 70 means, of bars pivotally secured to the section, means securing the bars to the supporting means, and means connected with the bars and controlled by a lever for raising the door and automatically locking it in the 75 raised position, as and for the purpose specified.

2. In a device of the class described the combination with the lower section of the door and suitable overhead supporting 80 means, of opposing bars pivotally secured to the door section and having their upper ends secured to the supporting means, a rotatable cross bar carried by the section, and oppositely directed links connecting the 85 cross bar with the lower ends of the pivoted bars, as and for the purpose specified.

3. In a device of the class described the combination with the lower section of the door and suitable overhead supporting 90 means, of opposing bars pivotally secured toward their lower ends to the section, chains securing the upper ends of the bars to the supporting means, a rotatable bolt passing through the section and having a 95 cross bar secured to one of its extending ends and a lever to the other, and oppositely directed links pivotally secured at their opposite ends to the lower ends of the pivot bars and at their adjoining ends to the cross bar, 100 said links being bent so as to lock the section in a raised position by the turning of a lever, as and for the purpose specified.

Signed at Winnipeg, in the Province of Manitoba, this 23rd day of June, 1909.

CHARLES HENRY KENNY.
MALCOLM McMILLAN.
